HARRY G. LEE, OF TACOMA, WASHINGTON, ASSIGNOR OF ONE-HALF TO EARL H. ROBBINS, OF TACOMA, WASHINGTON.

POSITION-INDICATOR FOR ELEVATORS.

1,197,507.

Specification of Letters Patent.

Patented Sept. 5, 1916.

Application filed March 25, 1915. Serial No. 16,876.

To all whom it may concern:

Be it known that I, HARRY G. LEE, a citizen of the United States, residing at Tacoma, in the county of Pierce, State of Washington, have invented certain new and useful Improvements in Position-Indicators for Elevators, of which the following is a specification.

This invention relates to devices adapted to be placed in one elevator cage for indicating the position of another elevator cage, and has for its objects to provide a simple, cheap, and effective means whereby the operator of the elevator car in which the device is mounted may at all times know the position and direction of motion of the other car by which this device is actuated.

A further object is to provide a device which will indicate the direction of motion 20 of the said car without the addition of a special electric circuit for the purpose.

I attain these and other objects by the devices, mechanisms, circuits and arrangements illustrated in the accompanying drawings, in which—

Figure 1 is a side elevation of the indicating mechanism, the side of its containing box having been cut away to reveal its interior; Fig. 2 is a view comprising a front view of the indicating mechanism together with a perspective view of the controlling device and, in diagrammatic form, showing the wiring connection between said indicating mechanism and said controlling device, 35 and the mechanical connection between the controlling device and the elevator mechanism.

Similar numerals of reference refer to similar parts throughout the several views.

Where more than one elevator is used in an office or other building it is a difficult matter to so operate them that they will be timed to give the best and most rapid service. For this reason it has been the custom to use special employees to start the elevators from the ground floor at uniformly spaced intervals, or for one elevator to ring a gong or flash a light when it has reached a predetermined point.

One of my devices is mounted in an elevator for each other elevator in the service and indicates to the operator the position and direction of motion of each of the said other cars, thus eliminating the necessity of

a special starter and enabling the cars to 55 maintain an established spacing throughout their trips.

In the drawings one elevator is shown and one indicator instrument operated thereby, it being understood that said instrument 60 may either be placed in another car or may be located at any other convenient place. The elevator 1 is suspended by a cable 2 which passes from a suitably driven and controlled drum 3. The said drum 3 is connected by suitable gears 4 or other appropriate devices to a spindle 5 which is therefore driven by the said drum. The spindle 5 is mounted on and passes through a disk 6 of insulating material on which are also 70 mounted four rings 7, 8, 9 and 10 each of which is concentric with said spindle 5. An arm 11 is mounted on the spindle 5 and turns therewith. The said arm 11 turns through a definite angle when the car 1 traverses the distance from one floor to another, the value of said angle depending on the 75 gearing 4 and the arrangement of the cable 2. A series of contact plates 12 are mounted in a circular path, preferably outside of 80 the ring 10, said plates being so spaced that the arm will pass from one to the next adjacent plate when the elevator passes from one floor to the next. The space between said plates 12 is preferably filled level with their 85 surface with a suitable insulating material 13. All the contact plates 12 are electrically connected together by a conductor 14 and are all also connected to one terminal 15 of the main electric circuit from which the energy 90 necessary for the actuation of the device is derived in the usual way. The other terminal 16 of the said main circuit is connected to the inner ring 7. The arm 11 is preferably made of insulating material and carries 95 a brush 17 engaging the said ring 7. The brush 17 is electrically connected to a conductor plate 18 mounted on the arm 11 and having two contact lugs 19 and 20 extending upward therefrom. A pair of contact 100 brushes 21 and 22 are pivotally mounted on opposite sides of the arm 11. The brush 21 is positioned to contact with the ring 8 at all times and swings on its pivot to engage the contact lug 19 of the plate 18 (as shown) 105 when the arm 11 is moving in a clockwise direction but to be disengaged therefrom when the arm moves in the opposite direc-

tion; therefore the ring 8 is electrically connected to the ring 7 through the brush 17, plate 18, lug 19, and brush 21 when the arm 11 moves in a clockwise direction. The brush 22 is oppositely mounted to contact with the ring 9 and swings on its pivot to engage the contact lug 20 of the plate 18 when the arm 11 is moving in a counterclockwise direction, but to be disengaged therefrom (as shown) when the arm moves in a clockwise direction; therefore the ring 9 is electrically connected to the ring 7 through the brush 17, plate 18, lug 20 and brush 22 when the arm 11 moves in a counterclockwise direction. The arm 11 also carries a double brush 23 which contacts with the ring 10 and with the contact plates 12 as it moves therewith, thus intermittently connecting the ring 10 with the main circuit 15 through the brush 23. The arm 11 turns in a clockwise direction when the elevator is traveling downward, as shown, and in a counterclockwise direction when the elevator is moving upward.

The instrument which indicates the location of the elevator and its direction of motion is electrically connected to the rings 8, 9 and 10 as hereinabove described and consists of a box or container 30 having a hole 31 in its face through which the number of the floor at which the car is positioned and the direction in which it is moving is seen. A disk 32 is revolutely mounted in the box 30 near its front face and is provided with a series of consecutive numbers corresponding with the floors of the building. The disk 32 has a series of teeth or pins 33 extending from its rear face, one such pin being provided for each floor. A series of notches 34 are made in the edge of the disk 32 and a spring 35 presses therein thus keeping the disk from being shaken or jolted out of its proper position. A pair of electromagnets 36 and 37 are mounted in the box 30, one on each side of the axis of the disk, as shown, both of said magnets being connected at one terminal with the common wire 38 which passes to the above described outer ring 10. The other terminal of the magnet 36 is connected by a wire 39 to the ring 9, and the other terminal of the magnet 37 is connected by the wire 40 to the ring 8. The armatures, and the operating mechanisms attached thereto, of each magnet are similar and therefore a description of one only is given; they are however mounted to engage pins on opposite sides of the disk. The armature 41 is lifted upward by the electromagnet when it is energized and carries an extension 42 above it. The extension 42 has a pivoted foot or pawl 43, mounted on its upper end, which is adapted to engage under the teeth or pins 33 to push them upward, but to turn on its pivot out of the way of said pins as the said armature and its ex-

tension passes downward to its normal unenergized position. The pawl of the magnet 36 thus causes the disk 32 to turn in a clockwise direction when the elevator is moving upward, said motion of the disk 70 causing the number of the next higher floor to appear opposite the hole 31 when the brush 23 has made contact with the next plate 12, and as each such plate 12 is thus engaged the magnet is energized and the 75 disk turned one notch and indicates one higher floor. Similarly the pawl of the magnet 37 causes the disk 32 to rotate in a counterclockwise direction when the elevator is moving downward, thus causing the indicated number to be reduced by one unit 80 every time the brush 23 engages the plates 12. Thus it will be seen that the disk will always show the number of the floor at which the elevator is positioned. 85

Now, in order to indicate in which direction the elevator is traveling I mount a carrier 44 on the pivot 45 at a point centrally positioned between the two magnets 36 and 37 and below the disk 32, said carrier having 90 an arm 46 extending toward the left and adapted to be engaged by a pin 47 on the extension 42 of the armature of the magnet 36, and also an opposite arm 48 similarly adapted to be engaged by a pin 49 on the 95 corresponding parts of the magnet 37. Two arms 50 and 51 also extend from the upper end of the carrier 44, in line with the lower part of the hole 31, the arm 50 having the legend "Up" imprinted thereon while the 100 arm 51 has "Down" imprinted thereon. A pair of notches are made in the carrier near the pivot 45 thereof, and a spring 52 engages either the one or the other to hold it in position. When a magnet is energized it 105 raises the extension 42 and the pin 47 or 49 thereof. When the elevator starts to go down then the first action of the "down" magnet 37 when it is energized, causes the pin 49 to engage the arm 48 and tip the carrier 44 so that the "down" arm 51 comes opposite the hole 31, as shown; afterward, each additional time the said magnet is energized for each floor that is passed downward by the elevator, the carrier remains in 110 said position. But, as soon as the "up" magnet 36 is energized, the pin 47 engages the arm 46 and throws the carrier to its other position so that the "up" arm 50 comes in line with the hole 31. This apparatus therefore is installed and operates in the following manner:—One indicating box 30 is placed at each point where it is desired to watch the movements of the elevator by which it is operated; for instance, one box 115 may be in the office of the building engineer; another in that of the building manager; and one in each other elevator in the building. The elevator, as it moves from one floor to another, causes one electric impulse to pass 120

125

through one or the other magnet 36 or 37 in each of the said boxes 30 in the circuit because the circuit is completed by contact with the plate 12 and through one or the 5 other disks 8 or 9, as the case may be. This impulse actuates the armatures of the said magnets and turns each disk 32 one notch so that the floor indicated through the hole is raised or lowered one integer in each box 10 30. If the elevator is at the bottom of the shaft, the disks 32 of all the boxes 30 controlled thereby will show the numeral 1, but as soon as it moves, therefrom to the 2nd floor the up magnet 36 in each box is energized 15 and the armature 41 is lifted, thus moving the disk to indicate "2" and also moves the carrier 44 so that the legend "Up" is also exposed through the hole, thus indicating to the engineer, manager, and each 20 operator of the other elevators that this elevator is at the 2nd floor and is going up. This is continued as each floor is reached until the elevator starts down, when the down magnet 37 in each box 30 is energized, 25 thus causing the disks 32 to turn back one notch to indicate one less number for the floor and also moving the carrier 44 so that the legend "Down" is exposed and indicating that the elevator is moving downward.

Having described my invention, what I claim is:

In a device of the class described, the combination with a box having an indicator opening therein; a pair of electro-magnets within the box; rotatable means mounted 35 within the box and actuated by either of said magnets through a unit distance in one direction or the other and adapted to indicate through the hole the position of a moving car; a pair of electric circuits, of each 40 of which one of said magnets forms a part; means operated by the moving car and adapted to intermittently complete one or the other of said circuits when the car reaches a series of predetermined places 45 traveling in one direction or the other, whereby said means is rotated a unit distance in one direction or the other each time the circuit is thus completed; and means mounted within the box and operated by 50 said magnets whereby the last magnet energized is indicated at said opening to indicate the direction of motion of said moving car.
